DEVICE FOR AUTOMATICALLY ARRANGING THE
ELEMENTS OF SLIDING CLASP FASTENERS

Filed Dec. 10, 1931

Inventor:
Karl Friedrich Nägele

UNITED STATES PATENT OFFICE

KARL FRIEDRICH NÄGELE, OF BERLIN-NEUKOLLN, GERMANY

DEVICE FOR AUTOMATICALLY ARRANGING THE ELEMENTS OF SLIDING CLASP FASTENERS

Application filed December 10, 1931, Serial No. 580,118, and in Germany May 17, 1930.

The invention relates to an improved device for automatically arranging the elements of sliding clasp fasteners preparatory to fixing them to the parts to which they are to be applied.

The object of the invention is to space such elements uniformly and all with the same orientation so that they may be correctly fixed by suitable machinery without the necessity of hand sorting.

According to the invention such a device comprises a rotating drum into which the elements are fed at random and which is provided with a slot having notches on one side adapted to engage the projections of the elements, and means for moving each element in succession in the same manner so as finally to bring them all into the correct orientation.

Other features of the invention will be explained by means of the accompanying drawing representing one form of the device with explanatory figures of the elements themselves, in which

Figure 1 is an elevation of an element and Figure 2 is a sectional side elevation of the same.

Figure 3 is a front elevation of the arranging device taken in section on the line 3-3 of Figure 4.

Figure 4 is a side elevation of the same taken in section on the line 4-4, of Figure 3.

Figure 5 is a sectional plan partly broken away and taken on the line 5-5 of Figure 4.

The elements intended for assembly are fed at random into a drum *a* shown in Figures 3 and 4 provided with one or more circumferential slots *k*. These slots have notches *b* at one side only which permit the

elements to emerge with only one orientation, namely that in which the projections *m* shown in Figure 2 lie towards the right-hand side in the view according to Figure 4, i. e. take up the position shown in Figure 2.

Thus oriented the elements pass to a space *n* provided with an overflow *d* from which any elements in excess of requirements passing out from the drum *a* are led away. From this space *n* the elements pass to a magazine *c*. From this magazine each element must

be taken in a particular orientation, namely, in the example shown, in such a manner that its head with the projection *m* is directed downwards and the two legs *o* upwards, as indicated in the lower part of Fig. 3. As in 55 the example shown the elements slide down the oblique walls of the space *n* with the legs directed downwards (position I, Fig. 3), they must be turned over, for which purpose they pass into a widened part *g* of the magazine 60 *c* in which there is a transverse pin *h*. This pin serves as a stop for the one leg of the element and turns the latter first into the position II, from which it is then tipped by gravity into the position III. From the magazine 65 *c* the elements now fall into a conveying device to be subsequently described.

As the elements are very small and light there may be provided according to a further feature of the invention a vibrator which sets 70 the whole arrangement into vibration so that the elements slide more easily in the guide channels and slots. This vibrator comprises a rod *p* which is urged by a spring *z* against a cam *q* fast with the shaft *r*. When during 75 the rotation of the cam *q* the highest part of the latter has passed the rod *p* this rod is released and thrown by the spring *z* against the wall of the magazine thus giving it a shock which is transferred to the elements. 80

Below the magazine *c* and on either side of the same are located two members *s* cut with screw threads, one left-handed the other right-handed. The members rotate in opposite direction and the distance between them and the pitch of the threads is such that chamberlike hollows are formed between the threads which are of just the right size to accommodate one element each. As the 85 members rotate each element is conveyed in the direction of the axes of the members from the opening of the magazine. To prevent the element from falling through between the members *s* a supporting strip *t* is 90 arranged between the members. 95

The effect of the screw thread is that the elements are arranged at an absolutely uniform distance from each other and by suitably selecting the pitch of the screw and the 100

width of the groove a correct spacing and fitting of the elements can be obtained.

The elements thus arranged are passed to the machinery which closes the legs of for fixing them to the article which is to be provided with this kind of fastening. It will be seen that the device according to the invention feeds this machine correctly without the necessity of hand intervention for the arranging of the elements.

10 A plurality of devices as described above can be mounted next to each other, thus providing for multiple feeding and economizing in the number of conveying members required.

15 What I claim is:—

1. A device for automatically arranging the elements of sliding clasp fasteners in correct relative location for assembly on the articles to which they are to be applied, comprising a rotating drum with a circumferential slot of width substantially equal to the thickness of an element, the said slot having notches on one side only not greatly exceeding in size the projection on the face of an element, an element receiving guide track and receiving and conveying means for the elements in the form of two cooperating members rotating in opposite directions and provided with left- and right-hand screw threads.

2. Devices for automatically arranging the elements of sliding clasp fasteners in correct relative location for assembly on the articles to which they are to be applied, each comprising a rotating drum with a circumferential slot of width substantially equal to the thickness of an element, the said slot having notches on one side only not greatly exceeding in size the projection on the face of an element and an element receiving guide track, in combination with receiving and conveying means for the elements in the form of screw-threaded members common to two elements arranging devices.

3. A device for automatically arranging the elements of sliding clasp fasteners in correct relative location for assembly on the articles to which they are to be applied, comprising a rotating drum with a circumferential slot of width substantially equal to the thickness of an element, the said slot having notches on one side only not greatly exceeding in size the projection on the face of an element, an element receiving guide track and receiving and conveying means for the elements in the form of screw-threaded members with a supporting strip therebetween.

4. A device for automatically arranging the elements of sliding clasp fasteners in correct relative location for assembly on the articles to which they are to be applied, comprising a rotating drum with a circumferential slot of width substantially equal to the thickness of an element, the said slot having

notches on one side only not greatly exceeding in size the projection on the face of an element, an element receiving guide track and receiving and conveying means for the elements in the form of two cooperating members rotating in opposite directions, adjustable as to relative distance and provided with left- and right-handed screw threads.

5. A device for automatically arranging the elements of sliding clasp fasteners in correct relative location for assembly on the articles to which they are to be applied, comprising a rotating drum with a circumferential slot of width substantially equal to the thickness of an element, the said slot having notches on one side only not greatly exceeding in size the projection on the face of an element, an element receiving guide track, a sliding track provided with a widened part and a transverse pin located therein to catch the trailing leg of each element.

6. A device for automatically arranging the elements of sliding clasp fasteners in correct relative location for assembly on the articles to which they are to be applied, comprising a rotating drum with a circumferential slot of width substantially equal to the thickness of an element the said slot having notches on one side only not greatly exceeding in size the projection on the face of an element and having a direction intermediate between radial and tangential, an obliquely directed element receiving guide track provided with an overflow, a vertical sliding track in continuation thereof constituting a magazine and provided with a widened part, a transverse pin located therein to catch the trailing leg of each element and receiving and conveying means for the elements in the form of two cooperating members rotating in opposite directions, provided with left- and right-handed screw threads and having an element supporting strip between them.

7. A device for automatically arranging the elements of sliding clasp fasteners in correct relative location for assembly on the articles to which they are to be applied, comprising a drum consisting of two parts juxtaposed to constitute therebetween a circumferential slot of width substantially equal to the thickness of an element, one of said drum parts having in its edge which constitutes one side of the slot notches not greatly exceeding in size the projection on the face of an element, means for rotating the two drum parts in unison and an element receiving guide track.

In testimony that I claim the foregoing as my invention, I have signed my name.

KARL FRIEDRICH NÄGELE.
